E. L. JOHNSON.
FLASH LIGHT APPARATUS.
FILED OCT. 22, 1925.

UNITED STATES PATENT OFFICE.

EVERARD L. JOHNSON, OF PATCHOGUE, NEW YORK.

FLASH-LIGHT APPARATUS.

Application filed October 22, 1921. Serial No. 509,673.

To all whom it may concern:

Be it known that I, EVERARD L. JOHNSON, a citizen of the United States, and residing at Patchogue, L. I., in the county of Suffolk 5 and State of New York, have invented certain new and useful Improvements in Flash-Light Apparatus, of which the following is a specification, such as will enable those skilled in the art to which it appertains to 10 make and use the same.

This invention relates to flash-light apparatus and particularly to the flash bag or cabinet of apparatus of this class, and the object of the invention is to provide an improved bag supporting frame which is so constructed as to permit of the folding or collapsing of said framework and the extension of the same into an oblong position; a further object being to provide means for 20 receiving and removing the dust or ash of the explosive medium employed and which collects in said flash bag or cabinet; and with these and other objects in view the invention consists in an improved apparatus 25 of the class specified which is simple in construction and efficient in use, and which is constructed as hereinafter described and claimed.

The invention is fully disclosed in the 30 following specification, of which the accompanying drawing forms a part, in which the separate parts of my improvement are designated by suitable reference characters in each of the views, and in which:—

Fig. 1 is a back view of the bag or cabinet showing the framework thereof in an extended position;

Fig. 2 a partial section on the line 2—2 of Fig. 1;

Fig. 3 a plan view of the construction shown in Fig. 1;

Fig. 4 a view similar to Fig. 1 but showing the parts in a different position and with part of the construction omitted;

Fig. 5 a partial section on the line 5—5 of Fig. 1 on an enlarged scale; and,

Fig. 6 a partial section on the line 6—6 of Fig. 2 on an enlarged scale.

In the drawing I have shown at 10 a 50 flash bag or cabinet composed of any suitable flexible fireproof material, and said bag, in the construction shown, is approximately triangular in form in cross section and comprising a back wall 11, a top wall 12, side

walls 13 and an angularly arranged front 55 wall 14, the bottom edges of the back wall 11 and front wall 14 are secured to a longitudinal base 15 provided with an aperture 16 which opens upwardly into the bag 10 and outwardly through the bottom of said 60 base, and a suitable shutter device 17 mounted in the base 15 is adapted to normally close the aperture 16, said shutter being operated by means of a crank 18 extending through one end wall of the base 15, 65 as shown in Fig. 6. The base 15 is provided with a removable cover plate 19 secured in position by catch or hook devices 20 at the ends thereof, and said cover plate is provided with an aperture 21 which registers with the aperture 16 in the base 15, 70 and the bottom of the cover plate 20 is provided with a sack 22 preferably composed of flexible material.

The bag 10 is adapted to be supported in 75 the position shown in Figs. 1, 2 and 3 of the drawing by a suitable framework 23 comprising, in the construction shown, a central frame member 24, a top frame member 25, and a bottom frame member 26. 80 The frame members 24, 25 and 26 extend longitudinally of the back wall 11 of the bag when in use, and said back wall is secured thereto, and the bottom member 26, in the construction shown, is formed by the 85 base 15 of the bag 10, and two movable frame members 27 are pivotally mounted in connection with the frame member 26 or base 15 as shown at 28 and are adapted to be extended vertically at the opposite sides of 90 the frame 23 and to be held in such position by clamps 29 which frictionally engage said frame members 27, and said clamps are operated by milled nuts 30 mounted on pins or bolts 31 secured or 95 mounted in the end portions of the frame members 24 and 25.

The upper edge of the front wall 14 of the bag 10 and the front edge of the top wall 12 thereof are secured to a strip 32 100 which extends longitudinally of the bag and brace rods 33 are preferably arranged in the manner shown in Fig. 3 of the drawing, and these rods serve to support the strip 32 in proper position to hold the front wall 105 14 of the bag 10 in a taut or drawn position, and by adjusting the frame members 24 and 25 vertically on the frame members

27 the back wall 11 of the bag may be also drawn and held in a taut position.

The central frame member 24 of the frame 23 is enlarged centrally thereof as shown at 5 36 and provided with a door 37 which normally closes an opening in the enlargement 36 of the frame 24, and this door permits of the placement of the explosive medium employed in apparatus of this class in proper 10 position on a flash gun of any kind or class, such as usually employed in apparatus of this class, and a tripod or other support may be connected with a keeper 39 on the enlargement 36 of the frame member 24 for 15 supporting the bag and the framework thereof in a predetermined position relative to a floor or in a room or compartment.

It will be apparent that by loosening the winged nuts 30, the frame members 24 and 20 25 may be dropped downwardly and the frame members 27 moved into a horizontal position as shown in Fig. 4 of the drawing, and the brace rods 33 may be detached from the keepers 34 and the strip 32 moved 25 into juxtaposition to the top frame member 25 as indicated in dotted lines in Fig. 3, and the brace rods 33 folded into an approximate parallel position to said strip. In the use of the apparatus and after a flash 30 has been produced in the bag 10 in the usual manner the dust or ash of the explosive medium employed will settle upon the inner face of the walls of the bag and upon the top of the base 15 as well as the shutter device 17 therein, and by raising said shutter device and brushing the exterior of the bag 10, or the walls 11, 13 and 14 thereof, this dust or ash may be moved downwardly and collected in the sack 22 suspended from the 40 cover plate 19, and after the apparatus has been used for a number of flashes the cover plate 19 may be removed and the dust or ash discharged therefrom in a suitable place.

Heretofore it has been customary and 45 necessary to remove the bag from its holder and shake it to remove the dust therefrom through an opening or slit in the bottom of the bag, and such bags as heretofore constructed have either been loosely suspended 50 from a tripod, or mounted in connection with a fixed frame, while with my improvement the bag supporting frame may be knocked down to a comparatively small package and the bag folded in connection 55 therewith to facilitate the shipment or carrying of the apparatus from place to place, especially in the use of such apparatus by photographers in taking photographs in the home of individuals, and while I have shown 60 certain details of construction in carrying my invention into effect, it will be understood that I am not necessarily limited to these details, and various changes therein and modifications thereof may be made, 65 within the scope of the appended claims,

without departing from the spirit of my invention or sacrificing its advantages.

Having fully described my invention, what I claim as new and desire to secure by Letters Patent, is:—

1. An apparatus of the class described comprising a framework composed of a plurality of movably connected parts, a flexible bag or cabinet mounted in connection with said framework, and said framework being 75 adapted to support said bag in an extended or operative position, and a sack detachably mounted in connection with the lower edge portion of said bag and into which the dust or ash of the explosive medium employed 80 is adapted to pass.

2. An apparatus of the class described comprising a framework composed of a plurality of movably connected parts, a flexible bag or cabinet mounted in connection 85 with said framework, and said framework being adapted to support said bag in an extended or operative position, a sack detachably mounted in connection with the lower edge portion of said bag and into which the 90 dust or ash of the explosive medium employed is adapted to pass, and means for controlling the communication between said bag and said sack.

3. An apparatus of the class described 95 comprising a framework composed of a plurality of horizontal frame members, other frame members adapted to cooperate with said horizontal frame members to support the same in predetermined positions relative 100 to each other, a flash bag mounted in connection with said frame members and extending forwardly therefrom, means cooperating with one of said frame members for supporting said bag in an extended position, 105 another of said frame members constituting the base of said bag and being provided with an elongated aperture, and a dust or ash receptacle detachably mounted in connection with said base framework.

4. An apparatus of the class described comprising a framework composed of a plurality of horizontal frame members, other frame members adapted to cooperate with said horizontal frame members to support the same in predetermined positions relative to each other, a flash bag mounted in connection with said frame members and extending forwardly therefrom, means cooperating with one of said frame members for supporting said bag in an extended position, 115 another of said frame members constituting the base of said bag and being provided with an elongated aperture, a dust or ash receptacle detachably mounted in connection 120 with said base framework, and a shutter device for controlling the passage of dust or ash into said receptacle.

5. An apparatus of the class described comprising a framework composed of top 125

- and bottom frame members and an intermediate or central frame member, means movably connected with one of said frame members and detachably mounted in connection with the other of said frame members for supporting the same in predetermined positions, a flexible flash bag mounted in connection with said frame members, said bottom frame member constituting the base 10 of said bag and being provided with an elongated aperture, a dust or ash receptacle mounted in connection with said bottom or base frame member and into which dust or ash from said bag is adapted to pass, means 15 for controlling the communication between said bag and said receptacle, and means mounted in connection with the top frame member for supporting said bag in an extended position.
- 20 6. An apparatus of the class described comprising a framework composed of top and bottom frame members and an intermediate or central frame member, means movably connected with one of said frame members and detachably mounted in connection with the other of said frame members for supporting the same in predetermined positions, a flexible flash bag mounted in connection with said frame members, said bottom frame member constituting the base 25 of said bag and being provided with an elongated aperture, a dust or ash receptacle mounted in connection with said bottom or base frame member and into which dust or ash from said bag is adapted to pass, means 30 for controlling the communication between said bag and said receptacle, means mounted in connection with the top frame member for supporting said bag in an extended position, and said central frame member being provided with an enlarged portion having a door opening which communicates with the interior of said bag, and a door for normally closing said opening.
- 35 7. An apparatus of the class described comprising a framework composed of top and bottom frame members and an intermediate or central frame member, means movably connected with one of said frame members and detachably mounted in connection with the other of said frame members for supporting the same in predetermined positions, a flexible flash bag mounted in connection with said frame members, said bottom frame member constituting the base 40 of said bag and being provided with an elongated aperture, a dust or ash receptacle mounted in connection with said bottom or base frame member and into which dust or ash from said bag is adapted to pass, means 45 for controlling the communication between said bag and said receptacle, means mounted in connection with the top frame member for supporting said bag in an extended position, and said central frame member being provided with an enlarged portion having a door opening which communicates with the interior of said bag, and a door for normally closing said opening.
- 50 8. An apparatus of the class described comprising a framework composed of top and bottom frame members and an intermediate or central frame member, means movably connected with one of said frame members and detachably mounted in connection with the other of said frame members for supporting the same in predetermined positions, a flexible flash bag mounted in connection with said frame members, said bottom frame member constituting the base 55 of said bag and being provided with an elongated aperture, a dust or ash receptacle mounted in connection with said bottom or base frame member and into which dust or ash from said bag is adapted to pass, means 60 for controlling the communication between said bag and said receptacle, means mounted in connection with the top frame member for supporting said bag in an extended position, and said central frame member being
- provided with an enlarged portion having a door opening which communicates with the interior of said bag, a door for normally closing said opening, and means for connecting a tripod or other support in connection with said central frame member. 70
8. An apparatus of the class described comprising a collapsible framework composed of a plurality of horizontal frame members, other frame members adapted to be extended into vertical position and to cooperate with said horizontal frame members to support the same in predetermined positions relative to each other, a flash bag mounted in connection with said frame members and extending forwardly therefrom, and means cooperating with one of said horizontal frame members for supporting said bag in an extended position. 75
9. An apparatus of the class described comprising a collapsible framework composed of top and bottom frame members and an intermediate or central frame member, means movably connected with one of said frame members and detachably mounted in connection with the other of said frame members for supporting the same in predetermined positions, and a flexible flash bag mounted in connection with said frame members. 80
10. An apparatus of the class described comprising a collapsible framework composed of top and bottom frame members and an intermediate or central frame member, means movably connected with one of said frame members and detachably mounted in connection with the other of said frame members for supporting the same in predetermined positions, a flexible flash bag mounted in connection with said frame members, and means mounted in connection with the top frame member for supporting said bag in an extended position. 85
11. An apparatus of the class described comprising a collapsible framework composed of top and bottom frame members and an intermediate central frame member, vertical frame members pivoted to the opposite ends of the bottom frame member and adapted to be detachably connected with the ends of the top and central frame members and serving to support said frame members in an extended position, and a flash bag mounted in connection with said frame members. 90
12. An apparatus of the class described comprising a framework composed of top and bottom frame members and an intermediate central frame member, vertical frame members pivoted to the opposite ends of the bottom frame member and adapted to be detachably connected with the ends of the top and central frame members and serving to support said frame members in an extended position, a flash bag mounted in connection with said frame members, means 95

- 105
- 110
- 115
- 120
- 125
- 130

mounted in connection with the top frame member and said bag for supporting said bag in an extended position, and means for mounting a tripod in connection with said 5 central frame members.

In testimony that I claim the foregoing as my invention I have signed my name in

presence of the subscribing witnesses this 17th day of Oct., 1921.

EVERARD L. JOHNSON.
